UNITED STATES PATENT OFFICE.

JOSEPH M. LITCHFIELD, OF SAN FRANCISCO, CALIFORNIA.

DESIGN FOR A BUTTON.

SPECIFICATION forming part of Design No. 25,114, dated February 4, 1896.

Application filed September 25, 1895. Serial No. 563,660. Term of patent 7 years.

To all whom it may concern:

Be it known that I, JOSEPH M. LITCHFIELD, a citizen of the United States, residing at San Francisco, in the county of San Francisco and State of California, have invented a certain new and useful Design for Buttons; and I do hereby declare the following to be a full, clear, and exact description of said invention, such as will enable others skilled in the art to which it most nearly appertains to make, use, and practice the same.

The drawing is the view of the front of a button having my design stamped thereon.

The leading feature of my design is the monogram of the interwoven letters "S" and "P," all centrally placed within and inclosed by the large letter "C," having between the

ends thereof the small letter "o." The central portion of the bend of the letter "S" is passed through the loop of the letter "P" to give ²⁰ the appearance of being supported thereby. These letters are inclosed within the raised edging of the button.

Having thus described this design, what I claim is—

The design for a button substantially as shown and described.

In testimony whereof I have hereunto set my hand this 18th day of September, 1895.

JOSEPH M. LITCHFIELD.
